DUST MOP ENVELOPE AND COMBINATION

Louise E. Winckler, San Francisco, Calif.

Application August 15, 1955, Serial No. 528,476

4 Claims. (Cl. 15—118)

Fig. 6 is a fragmentary semi-diagrammatic view illustrative of terry cloth structure of which the cover is preferably made.

In detail, the envelope illustrated comprises a blank 5 of terry cloth folded on itself at 1 (Fig. 3) to provide a straight outer edge, and opposed sides 2, 3 of corresponding shape.

The edge 1 may be called the outer or forward edge of the envelope and the edges 4, 5 of the blank that extend perpendicularly of edge 1 may be called the side edges 10 (Fig. 2). These side edges may extend convergently at 6, 7 (Fig. 2) toward the rear edge 8 of the envelope, and said side edges including the convergently extending edges 15 are stitched or secured together, while the edges 8 (rear edge of the envelope) are not secured together. Thus, a separable opening is provided along the rear edge for the mop head 9 (Fig. 1) to be inserted into the envelope.

A pair of snap fasteners 12 along said rear edge 8, and 20 equally spaced at opposite sides of a medial line extending through said envelope, provides means for releasably securing the open side of the envelope closed at opposite sides of handle 13 (Fig. 1).

These snap fasteners are to be considered illustrative of a simple, economical and easily attached means for 25 releasably securing the envelope on the mop head, but it is not intended to be restrictive, since there are other conventional fasteners that may be used. However, whatever means is employed, it is preferable that the means be of the type that will not cause the envelope to wrinkle 30 or be gathered, since the desired efficiency of the envelope comes from its flat sides remaining reasonably flat.

It should also be noted that, as seen in Fig. 4, the 35 snap fasteners are readily used when the envelope is reversed or in inside out position, and whatever type of fasteners are employed they should be usable in two positions, or when the envelope is reversed.

Within the envelope along edge 1, or along the fold line 40 of the blank from which the envelope is formed, is a straight, elongated member or strip 10 of sponge rubber or substantially the equivalent thereof insofar as having substantially the resiliency and moisture absorbent characteristics of sponge rubber are concerned.

The member 10 is preferably rectangular in cross sectional contour, and a line of stitching 11 secures the sides 45 2, 3 of the envelope together along the side of member 10 that is between the member and the mop head whereby a pocket is formed along edge 9 for said member, and this pocket snugly holds the member 10 with two of its opposite flat sides coplanar with the sides 2, 3 when the latter are flat. The ends of the member 10 terminate substantially at the corresponding ends of side edges 4, 5.

As seen in Fig. 3, the contour of the envelope enclosing the member 10 generally conforms in cross sectional contour to the cross sectional contour of the member, 55 hence when the forward or outer portion of the envelope is flat against the floor, as seen in Figs. 1 and 3, the lower flat surface of the envelope below the member 10 will be flat on the floor 1 and the forward lower corner of the envelope will substantially fit in the corner at the juncture between the side wall 15 and floor 14. Thus, 60 whether or not a quarter round or other molding is used at the juncture between the floor and wall, a corner of the envelope will fit in the angle produced, which would not be the case were the member 10 cylindrical. This 65 result is true when the envelope is reversed as seen in Fig. 5.

It should further be noted that the member 10 is preferably relatively thick, in cross sectional contour in both dimensions. Thus it will always tend to straighten out and to be flat when on the floor, which are characteristics 70 that are quite essential to the desired cleaning efficiency. Should there be projections on a floor or wall, the mem-

This invention relates to a launderable envelope or cover for a dust mop and has for one of its objects the provision of a more efficient cover than heretofore, and one that will retain its effectiveness through repeated launderings and which is provided with means for insuring a flat contact between the cover and floor along a straight outer edge that terminates in corners that are adapted to clean in room corners and crevices.

A still further object of the invention is the provision of an envelope for a dust mop that includes means for supplying moisture to one edge of the cover and which means also insures holding the cover flat along said edge yet permitting flexibility so that said edge will conform to the shape of obstructions, such as the legs of furniture, floor buttons, etc.

Heretofore, cloth covers or envelopes for brooms have been used, and attempts have been made to overcome the problem of cleaning in the corners of a room. Some such covers contemplate converting a broom into a mop by securing string material to the cover. These latter type of covers retain the same objections that are inherent in string mops, namely; the loose string ends that fling the dirt around. Other covers provide a marginal web or fin around the edges of the cover, but such a web curls and wrinkles, particularly after washing, and does not lie flat against the floor, thus leaving material on the floor that should be picked up, and since such curling or wrinkling may be at the corners of the cover as well as along the marginal portions, the intended purpose of the web or fin to facilitate cleaning in the corners of a room are defeated.

Applicant's envelope is primarily intended for use on a dust mop, and is effective whether damp or dry. However, provision is made for maintaining a dampened outer edge, which is desirable in many instances for cleaning along difficult base boards and corners where a dampened cloth is more effective than a dry one.

A still further object of the invention is the provision of a cover or envelope for a dust mop that is reversible so as to provide four different surfaces, all without impairing the efficiency of the mop in any position of the envelope. Where this has been attempted previously, it usually happens that efficiency is lost in one of the positions. This is not true in the present invention.

Other objects and advantages will appear in the description and drawings.

In the drawings,

Fig. 1 is a perspective view of a mop having the cover on the head, and positioned for cleaning in the corner of a room.

Fig. 2 is an enlarged top plan view of the mop head cover separate from a mop head, with right angle lines indicating a wall and floor.

Fig. 3 is an enlarged sectional view along line 3—3 of Fig. 2.

Fig. 4 is a plan view similar to that of Fig. 2, but showing the cover reversed, or inside out.

Fig. 5 is a sectional view along line 5—5 of Fig. 4.

ber 10 is soft and will readily yield under pressure to accommodate itself to any variations in the surface of the floor or wall.

The fact that the member 10 is preferably moisture absorbent, such as where it is of foam rubber, as distinguished from sponge rubber and the like, will enable it to carry a supply of moisture for gradual release to the portion of the envelope covering it so that the latter will remain damp. In many instances such dampness is particularly desirable, while the remainder of the envelope may remain dry.

The operator can readily moisten only the leading marginal portion of the envelope, if desired, and saturate the sponge rubber, after which the dusting operation can be performed and the said marginal portion will not only remain damp, but the moisture held by the member 10 will tend to make the leading portion hug the floor due to the added weight of the water.

The resiliency of the member 10 and its tending to straighten out at all times, whether wet or dry, prevents the mop from causing the envelope to bunch and to thereby lose its efficiency. The fact that the member 10 extends to the ends of the edges 4, 5 provides right angle corners at the junctures between edges 4, 5 and edge 1 that will fit into the corners of a room as seen in Fig. 1, and the member 10 will hold the corners of the mop and envelope against the floor at such corners, which result would not occur, except accidentally, were the member 10 omitted or were it not to extend to the corners.

While deep pile terry cloth is the preferred material, since it provides loops 16 on both sides of the material (Fig. 6) so thus providing the four dusting, cleaning, and polishing surfaces, the invention is not necessarily restricted to the use of such cloth. The dust collected by terry cloth readily shakes therefrom, and repeated use of such cloth on a surface will polish the latter.

It is seen from the foregoing that the use of the envelope not only overcomes the objection to the uncontrolled flying strings of a string or yarn dust mop, but the mop can be kept clean since the envelope can be more readily washed and dried than the mop head, and four separate clean surfaces are usable before the envelope is washed. Also, attempts to wash a mop head result in the metal fittings becoming wet and rusted, thus not only weakening the material of the mop, but also staining it. The use of present envelope will overcome this problem thereby materially adding to the life of the mop.

The details herein described in detail are not to be interpreted as being restrictive of the invention, but are merely illustrative of preferred structure.

I claim:

1. An envelope for the cleaning head of a dust mop comprising: a blank of cloth folded upon itself to provide a pair of opposed sides integrally joined along a straight line defined by the line of fold and corresponding edges extending away from the ends of said line of fold substantially normal to said line, means securing said corresponding edges together, the edges of said blank opposite said line of fold being separable for passage of the handle of such head when the latter is within said envelope, means for releasably securing said last mentioned edges together, and an elongated, resilient, soft stiffener of substantially greater thickness than said cloth secured between said sides along said line of fold for yieldably holding the corners of said envelope at the ends of said member extended to facilitate cleaning in corners, the space between said sides and between said elongated member

and said separable edges being free for insertion and withdrawal of said head independently of said member.

2. An envelope for the cleaning head of a dust mop comprising: a blank of cloth folded upon itself to provide a pair of opposed sides integrally joined along a straight line defined by the line of fold and corresponding edges extending away from the ends of said line of fold substantially normal to said line, means securing said corresponding edges together, the edges of said blank opposite said line of fold being separable for passage of the handle of such head when the latter is within said envelope, means for releasably securing said last mentioned edges together, and an elongated member having the resilient and moisture absorbent characteristics of foam rubber secured between said sides along said line of fold for yieldably holding the corners of said envelope extended, the space between said sides and between said elongated member and said separable edges being free for insertion and withdrawal of said head independently of said member.

3. An envelope for the cleaning head of a dust mop comprising: a blank of cloth folded upon itself to provide a pair of opposed sides integrally joined along a straight line defined by the line of fold and corresponding edges extending away from the ends of said line of fold substantially normal to said line, means securing said corresponding edges together, the edges of said blank opposite said line of fold being separable for passage of the handle of such head when the latter is within said envelope, means for releasably securing said last mentioned edges together, and an elongated member having the resilient and moisture absorbent characteristics of foam rubber secured between said sides along said line of fold for yieldably holding the corners of said envelope extended, said blank being of terry cloth to provide a corresponding cleaning surface formed of loops of thread on opposite surfaces of each of said sides whereby said envelope is reversible on a mop head, and said sides being secured together along the side of said member that is opposite to said line of fold so that said member will be fully enclosed by said cloth separate from the head of a mop that is adapted to be enclosed by said envelope.

4. In combination with the head of a string mop having a handle projecting from one side thereof, an envelope of terry cloth enclosing said head and through which said handle projects, said envelope having a straight edge along the side thereof opposite to said handle, which edge extends at right angles to said handle, an elongated pocket within said envelope along said straight edge and an elongated member of material having the resilient, moisture absorbent characteristics of foam rubber within said pocket extending from end to end thereof, said envelope having straight side edges extending perpendicularly from the ends of said straight edge and the ends of said member terminating at one of the ends of said side edges, means for releasably securing said envelope about said head at said handle, whereby said envelope may be removed and the said terry cloth providing corresponding opposite cleaning and polishing surfaces to said sides whereby said envelope may be reversed for using said opposite surfaces.
